UNITED STATES PATENT OFFICE.

JOSHUA C. REYNOLDS, OF OWENSBORO, KENTUCKY, ASSIGNOR TO WOODFORD F. AXTON
AND EDWIN D. AXTON, BOTH OF LOUISVILLE, KENTUCKY.

OIL BURNER.

Application filed June 16, 1924. Serial No. 720,312.

To all whom it may concern:

Be it known that I, JOSHUA C. REYNOLDS, a citizen of the United States, residing at Owensboro, in the county of Daviess and 5 State of Kentucky, have invented certain new and useful Improvements in Oil Burners, of which the following is a specification.

My present invention relates to oil burners and has for its object the provision of a 10 simple and compact burner whereby liquid fuel may be readily converted into a combustible vapor and heat economically generated thereby. Another object of the invention is to provide simple means whereby the 15 heat may be most advantageously utilized. Incidental objects of the invention will appear in the course of the following description.

In the annexed drawings:

20 Figure 1 is a plan view, partly broken away, of one embodiment of my present invention;

Fig. 2 is a side elevation of the same with 25 part in section;

Fig. 3 is an enlarged detail section on the line 3—3 of Fig. 1;

Fig. 4 is an enlarged detail horizontal section on the line 4—4 of Fig. 2, and

Fig. 5 is a detail section showing a burner 30 tip differing from the form shown in Fig. 1.

In carrying out my present invention, I provide a volute coil 1 which may be connected directly with a supply pipe 2 leading from any convenient reservoir or source of 35 supply. The several turns of the coil 1 will obviously successively decrease in diameter, the innermost turn of the coil defining an open space, indicated at 3, through which the flame from the jet spout 4 may rise.

40 From the inner extremity of the coil the pipe is carried downwardly, as shown at 5, and connected directly with a cut-off and regulating valve 6 which may be of any approved type. This valve 6 is arranged immediately adjacent the jet spout 4 which extends from one end of the valve casing and projects upwardly, being equipped with a jet opening 7 in its upper end. The stem of the valve 6 projects through and below the 45 valve casing and is flat-sided, as shown at 8

in Fig. 4, whereby it may fit closely within a slot 9 formed in the inner end of a handle or adjusting bar 10 which projects laterally from the valve to any desired extent and permits the valve to be easily adjusted without the user being directly exposed to the heat immediately at and adjacent the valve. 55 To maintain the operative relation and engagement of the handle member 10 and the valve stem, a connecting pin 11 is inserted 60 through the stem and the end of the handle, as clearly shown in Fig. 4.

The coil 1 is supported by a plurality of legs 12 which also support an ignition pan 13, the said pan being provided at intervals 65 with off-set lugs 14 having openings vertically therethrough to receive the legs 12, and set screws 15 being mounted in the said lugs to bear against the legs and thereby secure the pan in the proper position thereon. The 70 pan, will, of course, be arranged below the spout 4 so that the liquid fuel which may be permitted to overflow from the said spout, when starting the use of the burner, will be caught in the pan. The upper portions of the legs 12 are carried laterally radially outward, as shown at 16, and the coil 1 rests directly upon these lateral portions. 75 The extremities of the legs are turned upward, as shown at 17, to abut the outermost 80 turn of the coil, and clamp plates 18 are fitted upon the said upturned terminals 17 and project inwardly therefrom over the outermost turn of the coil 1, the inner edges of said clamp plates being turned slightly 85 downward, as shown at 19 in Fig. 3, whereby they will closely engage the circular surface of the coil pipe and will very securely hold the same to the supporting member 16 when the nut 20 which is mounted upon the terminal 17 is turned home.

In order to retard the flow of the liquid fuel through the coil and thereby assist in the vaporization of the same, I prefer to insert in the inner turns of the coil a cable 21 95 which may be of metallic material and which, when it is used, should extend from the end of the innermost turn of the coil to a point in the coil near the outermost turn of the same. Of course, the extent of this 100

cable may be varied to suit the wishes of the user and it may sometimes be entirely omitted.

I also employ a baffle 22 consisting of a metallic plate or body of sufficient diameter to extend over several of the inner turns of the coil but leave the outer turns uncovered. This body or plate may be given any desired configuration and preferably has one flat face and one convex face, as illustrated in the accompanying drawings. Radial arms 23 extend from this baffle which is circular in plan view, the arms and the plate being preferably cast as one integral structure. The arms have parallel edges 24 either of which may rest upon the coil 1 and said edges terminate in abutments 25 which conform to and are adapted to fit against the outermost turn of the coil 1 whereby the baffle will be supported over the coil in axial alignment with the jet spout 4. Obviously, when the burner is in use, the flame rising from the spout 4 will play upon the baffle 22 and will be thereby diverted or spread laterally so that it will then play over the upper surface of the coil 1 and raise the temperature thereof so that the liquid fuel flowing into and through the coil will be vaporized quickly and will be very easily and efficiently ignited as it issues from the jet spout. If the curved surface of the baffle be presented to the coil, the flame may pass more directly upward from the coil but, if the flat face of the baffle be presented to the coil, the flame will be held more closely to the coil and, consequently, the fuel will be more quickly vaporized. The intensity of the flame may thus be regulated and the heat therefrom utilized in the manner which may prove most efficient under any given circumstances. Of course, the intensity of the flame will be also to a great extent regulated by the adjustment of the valve 6. The legs 12 may rest upon a stove top or any other fixed support and will carry the coil and the burner in such a manner that they will be firmly supported but at the same time will be readily accessible at all times to facilitate cleaning or repairs.

When the burner is to operate, a small portion of the fuel may be permitted to overflow into the ignition pan 13 by opening the valve 6, or the pan may be otherwise filled. The fuel in the pan is ignited and the flame therefrom will play directly upon the spout 4 and the pipe 5 leading thereto so that the body of fuel in the pipe will be quickly vaporized. If the valve 6 be then opened, this vapor will issue at the opening of the jet spout 4 where it may be ignited and the burner will then continue to generate and consume the combustible vapor as long as the valve is permitted to remain open. The burning vapor will, of course, possess some velocity so that the greater

portion thereof will pass through the opening 3 and play upon the baffle which will divert it so that it plays over the coil 1 to assist in vaporization of the fuel flowing therethrough before rising around the baffle to be utilized in cooking or heating. The baffle and the arms extending therefrom will become heated as the operation of the burner continues and the heat thus stored in said elements will react on the coil so as to aid in the vaporization of the fuel, and in a short while the controlling valve 6 may be partly closed thereby retarding the flow of the fuel and economizing in the use of the same. The flame from the burner jet playing directly upon the central portion of the coil and the baffle plate holding the heat over the top of the coil, the fuel is automatically vaporized as it flows through the coil. The baffle and its supports are reversible according to the spread of flame which may be desired, and also furnish a very convenient support for cooking utensils as is obvious.

In Fig. 5 is shown a drain bowl 30 secured to the inner terminal 5 of the coil, a jet plug 31 being secured in the upper side of the bowl and a drain plug 32 being secured in the under side of the bowl in axial alignment with the jet plug. Suitable packing, indicated at 33, is provided to prevent leakage around the plugs.

Having thus described the invention, I claim:

1. A burner comprising a volute coil connected with a source of supply, a jet spout arranged below and in communication with the coil, supporting legs below the coil having their upper portions extending laterally outward whereby to bear against the under side of the coil and having their upper terminals upturned to abut the outermost turn of the coil, clamp plates mounted upon said upturned terminals and engaging over the outermost turn of the coil, and securing devices mounted upon said terminals and bearing upon said clamp plates.

2. A burner comprising a volute coil connected with a source of supply, a jet spout arranged below the coil and communicating therewith, supporting legs connected at their upper ends with the coil, and an ignition pan provided with lateral lugs through which the legs extend and having set screws mounted in said lugs to bind upon said legs.

3. A burner comprising a volute coil having its outermost turn connected with a source of fuel supply and having its innermost turn defining a central clear space, a jet spout arranged below the coil and in communication with the innermost turn of the same, means for supporting the coil, a baffle arranged above the central space of the coil, and arms extending radially from the baffle to rest on the coil and engage around the outermost turn of the same.

4. A burner comprising a volute coil having its outermost turn connected with a source of fuel supply and its innermost turn defining a central clear space, a jet spout arranged below the coil and in communication with the innermost turn thereof, means for supporting the coil, a reversible baffle arranged above the coil and over the central space of the same, and arms extending radially from the baffle and having their upper and lower edges parallel whereby either edge may rest upon the coil, said edges terminating in abutments adapted to engage the outermost turn of the coil. ¹⁰

In testimony whereof I affix my signature.

JOSHUA C. REYNOLDS.
